US00D898988S

(12) **United States Design Patent** (10) **Patent No.:** **US D898,988 S**
Levinson (45) **Date of Patent:** **** Oct. 13, 2020**

(54) **ATOMIZER CIGAR**

(71) Applicant: **LEVINSONVAPES,
INCORPORATED**, Tarzana, CA (US)
(72) Inventor: **Anthony Levinson**, Tarzana, CA (US)
(73) Assignee: **LEVINSONVAPES,
INCORPORATED**, Tarzana, CA (US)

(***) Term: **15 Years**(21) Appl. No.: **29/689,161**(22) Filed: **Apr. 26, 2019****Related U.S. Application Data**

(63) Continuation-in-part of application No. 29/627,909, filed on Nov. 30, 2017, now abandoned, which is a continuation-in-part of application No. 29/598,548, filed on Mar. 27, 2017, now Pat. No. Des. 814,103.
(51) **LOC (12) Cl.** **27-01**
(52) **U.S. Cl.** **USPC** **D27/101**
(58) **Field of Classification Search**
USPC D27/100, 101, 139–194; D23/202;

Primary Examiner — Marissa J Cash(74) *Attorney, Agent, or Firm* — Hankin Patent Law, APC; Kevin Schraven; Anooj Patel(57) **CLAIM**

The ornamental design for an atomizer cigar, as shown and described.

DESCRIPTION

FIG. 1 is a top perspective view of an atomizer cigar, showing my new design.

FIG. 2 is a bottom perspective view thereof.

FIG. 3 is a side elevational view thereof.

FIG. 4 is a side elevational view thereof.

FIG. 5 is a front elevational view thereof.

FIG. 6 is a back elevational view thereof.

FIG. 7 is a top plan view thereof; and,

FIG. 8 is a bottom plan view thereof.

The broken lines in the drawings depict portions of the atomizer cigar that form no part of the claimed design.

1 Claim, 8 Drawing Sheets# US D898,988 S
